UNITED STATES PATENT OFFICE.

LOUIS SCHWARTZBERG, OF CHICAGO, ILLINOIS.

CARTON OR BOX.

Application filed April 16, 1923. Serial No. 632,270.

To all whom it may concern:

Be it known that I, LOUIS SCHWARTZBERG, a citizen of the United States, residing at Chicago, in the county of Cook and State 5 of Illinois, have invented a new and useful Improvement in a Carton or Box, of which the following is a specification.

My present invention relates to cartons and boxes that are of cellular interior construction and are adapted for use in the packaging of eggs and other articles of commerce for conveniently dispensing small quantities of the articles for retail trade.

Primarily, my invention has for its object 15 the provision of a cellular carton that is distributed to the storekeeper in a collapsed or flat condition for convenient storage, and when needed for use may be readily and quickly opened and extended. To this end, 20 I have designed the walls and interior construction of my carton in a manner so that but a single operation is required to convert the same from a collapsed to an extended structure. Also I have provided means for 25 manipulating the cell walls of a carton of this character that may be employed either with the carton herein illustrated or may be employed with cellular cartons of other designs. A still further object resides in 30 providing a cellular carton wherein the exterior walls and cover, together with the cell walls and the means for moving the walls, is a unitary structure; that is, there are no loose parts that have to be inserted 35 or installed during or after the assembly or opening of the carton. Further objects will be apparent to others familiar with the art to which my invention appertains, all of 40 which I prefer to carry out in substantially the manner illustrated in the accompanying drawings that form a part of this specification.

In the drawings:

Fig. 1 is a perspective of a typical embodiment of my invention with the cover raised to disclose a portion of the interior.

Fig. 2 is a longitudinal section of one end of the carton.

Fig. 3 is a fragmentary perspective at one 50 end of the carton, partly broken away, and illustrating a manner of assembly.

Fig. 4 is a plan of means in the form of a false bottom for moving the hinged cell walls.

Fig. 5 is a schematic view in perspective 55 showing the assembly of the partition with

a cell wall operating means, of false bottom.

Fig. 6 is a fragmentary perspective illustrating the assembly of parts of the carton.

Fig. 7 is a plan of a false bottom to which 60 the cell walls are secured by cement.

Figs. 8, 9, and 10 are fragmentary vertical sections showing several modes of attaching the hinged cell walls to their operating 65 means or false bottom.

Fig. 11 is a plan or lay out of the blank for fabricating the carton in its preferred form.

Fig. 12 is a plan of a false bottom that is 70 designed to be employed with the carton made with a removable partition.

Fig. 13 is a fragmentary perspective of a carton with a removable partition.

Fig. 14 is an end view of a structure in 75 which the partition is integral with the bottom.

In the drawings, similar reference characters are employed to designate like parts wherever they occur throughout the several views, and by observing Figs. 1 and 11, it will be seen that the body of the carton, when opened in an extended position so as to be ready for use, comprises longitudinally elongated vertical front and rear walls A and B, respectively; a bottom wall C connecting the lower edges thereof; and a top member or wall D connecting the upper edges of the front and rear walls. A cover E extends from the rear or back wall B that has a hinged connection by forming a bend 80 e in the fabric of the structure at the juncture between these members so that the cover, whenever desired, may be folded down above the top wall. A lateral flange or flat F extends along the outer longitudinal edge of the cover and is formed with integral hooks f that are adapted to interlock with coacting portions of the carton 85 when the cover is lowered to close the carton.

One or more longitudinal partitions G 100 may be formed integrally from an intermediate portion of top wall D, which latter is provided first with upturned flanges 15, at the center of width of its portion of the blank and then bending the intermediate portion 16 of the fabric downwardly upon itself towards bottom C of the carton. If desired, this longitudinal wall may be a separate piece that is transversely slotted and inserted in interlocking slots in the usual manner of cell cartons, or may be formed 105 integrally from bottom C by folding up- 110

wardly an intermediate portion G' of the bottom wall portion of the blank, as illustrated in Fig. 14 of the drawings, in which latter event pieces G' may be secured together adjacent bottom C and the upper edge inserted in a groove or channel formed between flanges 15 of top wall D. The transverse or cell walls 17 are cut from the blank upon opposite sides of the flange portion thereof, and are normally flat with top wall D when collapsed, but are moved down to or near bottom C when the carton is opened and co-operate with partition 15 to divide the interior into a plurality of cube shaped cells disposed in rows on each side of said partitions. In making the cuts in the blank for transverse walls 17, suitable angular shaped corner connectors 18 are left in the top wall, which connectors, at the front edge of the carton, provide means to be engaged by hooks f of the locking flange of the cover when the carton is closed.

It is to the means for moving transverse cell walls 17 into opened or closed positions that my present invention relates, and said means includes a reciprocable false or supplementary bottom 19 of suitable dimensions that is above the bottom of the carton and is suitably connected to transverse walls 17 so that they may all be moved simultaneously whenever the structure is operated to open or collapse the carton. Divers means may be employed to connect the false bottom to the transverse walls, several of which structures I have herein illustrated in Figs. 3, 7, 8 and 9. In the preferred form, illustrated in detail in Figs. 1, 3 and 4 of the drawings, the transverse walls 17 are reduced slightly at their lower edges to provide extensions 20 that are provided with slots 21 extending parallel with the adjacent lower edges of the respective walls. The false bottom 19 is provided with a tongue 22 cut from the material of the bottom and adjacent the hinge of the tongue the false bottom is provided with a slot 23 upon each side of tongue 22 into which the reduced portion 20 of the transverse walls is adapted to be inserted. In this operation of inserting the extension into the slot 23, tongue 22 is entered into slot 21 of the transverse wall so that the latter is securely locked in position and coacts with false bottom 19. Each of the transverse walls is similarly constructed at its end opposite the hinge or corner pieces 18, and the false bottom is provided with a plurality of slots 23 and tongues 22 arranged in longitudinal rows and corresponding in number with transverse walls 17.

Another method of connecting transverse walls 17 to the false bottom 19 is shown in Figs. 7, 8 and 9, wherein suitable curved or crescent shaped cuts are formed in false bottom 19 so that short tongues or flanges

24 may be bent up from the body of the false bottom, and which are of segmental shape upon their outer edges. The transverse walls 17 in this instance are made slightly shorter than the walls heretofore described so that they will not contact the carton bottom C, and their lower edges are cemented or otherwise attached to either side of the tongue or flange 24, as shown in Figs. 8 and 9. In order not to cut false bottom 19, the lower edges of the transverse walls may be provided with laterally bent flanges 25, and the same secured to the false bottom at the locations where the segmental shaped flanges or tongues 24 would have been disposed, as shown in Fig. 10. It will be seen that by connecting the transverse walls to the false bottom permits the movement of all of the walls simultaneously so that by shifting the false bottom longitudinally of the carton in one direction the transverse walls will be moved to a horizontal or closed position for collapsing the carton, or by moving the false bottom longitudinally in the opposite direction the structure may be extended or opened and the transverse walls will be positioned vertically to divide the interior of the carton body.

It will be seen the false bottom is disposed upon opposite sides of the longitudinal partition G, and in order to permit of the collapsing of the carton in the manner just mentioned, I have provided the major portion of the false bottom with an elongated longitudinal slot 26 extending to the edge of the false bottom at one end where it has an offset that provides an end locking hook 27 and another oppositely arranged offset that provides an intermediate locking hook 28. The slot 26 is adapted to receive the lower portion of the longitudinal partition, and in the collapsed condition the slot will engage the partition adjacent the top wall, but after false bottom 19 has been moved longitudinally within the body of the carton to open or extend the same, the false bottom moves down towards the lower portion of the partition and locking hooks 27 and 28 will engage recesses 29 and 30 in one end and an intermediate adjacent portion of the partition. The inner end of slot 26 during this operation travels along the curved portion 31 of the adjacent end edge of the partition, and at the bottom thereof enters a V-shaped notch 32 adjacent the lower edge of the partition. During this movement of the false bottom hook 28 will be engaged with the adjacent side of the partition and will therefore cause a pivotal or leverage action between the adjacent side or half of the false bottom between the hook 28 and the end engaged by the notch 32. This will, under ordinary circumstances, cause buckling of the false bottom, or a probable wedging of said bottom against

one of the vertical walls of the carton body but in order to prevent this, I have slightly tapered edge 33 of the false bottom toward hook 27.

- 5 In securing the top wall or member to the remaining walls of the carton, I prefer to provide a securing flange *d* along the edge of top wall *D* adjacent the rear wall *B* and turn down this flange *d* and secure it to 10 the adjacent portion of the rear wall below the plane of the top wall. A modification of this securing structure is shown in Fig. 6 wherein flange *d* is bent upwardly, but not secured to the back wall and segmental shaped tongues *d'* are cut from the top wall, out of the adjacent portions of partition walls 17, and said tongues *d'* are glued or otherwise secured to back wall *B* at spaced intervals and below the plane of top wall 20 *D*.

In Fig. 13, I have shown the application of my collapsing and opening means to a carton of a well known type, which carton is provided with a removable partition wall. 25 In this structure, the partition walls are not spaced from each other as heretofore described, but form continuous walls 34 from the front to the rear and are each provided with a transverse slot 35 extending downward from their upper edges. The removable partition 36 is provided with interlocking recesses 37 that engage walls 34 below their slots 35. The lower portions of transverse walls 34 may be provided with any of 30 the means I have heretofore described for connecting the same with false bottom 38. For convenience, I have shown in this connection the structure illustrated in Figs. 7 and 8 of the drawings, in which tongues 24 are cut in false bottom 38 and are bent laterally and glued, or otherwise secured to the adjacent lower edges of the elongated transverse walls 34. In manipulating this 35 structure the removable partition 36 may be pressed against the flattened partition walls prior to assembly, and by a quick downward action against the same, after the body walls have been opened or extended, will force 40 partition walls 34 downward with false bottom 38 and slots 35 and 37 of the walls and partition will coat with each other in the assembly of the structure.

It is obvious that other methods may be 55 employed in carrying out this invention, and it is obvious that the false bottom 19 may, when the carton is in its open or non-collapsed position, be either flat against bottom *C* of the carton body, or may be spaced a slight distance therefrom, as seen in the drawings, which will provide a slight cushion for the articles in the cells. I desire it understood that all such changes and modifications are contemplated as coming fully 60 within the scope of my invention as expressed in the following claims.

What I claim is:—

1. A collapsible carton comprising front, rear and bottom walls, a plurality of transverse cell walls produced by slotting a blank from which they hinge at their top edges, a 70 separate flat strip connected to the lower ends of said cell walls controlling the relative positions of said cell walls, and a longitudinal partition.

2. A collapsible carton comprising front 75 and rear walls, top and bottom walls connecting the same, a plurality of transverse cell walls formed from said top wall and movable to positions transverse thereto, means connected to the cell walls above the 80 bottom wall for moving said cell walls into divers positions, and a longitudinal partition formed from one of the walls and intersecting said cell walls in non-collapsed position.

3. A carton comprising front, rear and bottom walls, a plurality of transverse cell walls, a false bottom connected to the end portions of said cell walls whereby the latter are moved to divers positions to open and 90 collapse said carton; said false bottom normally positioned parallel to the bottom wall of the carton, and a longitudinal partition intersecting said cell walls in non-collapsed position.

4. In a carton having a collapsible hollow body, a plurality of hinged cell walls co-operating therewith, and means for moving said walls upon their hinges consisting of a false bottom connected to the ends of said 100 walls opposite their hinges.

5. In a carton having a collapsible hollow body, a plurality of hinged cell walls co-operating therewith, and means for moving said walls upon their hinges consisting of a false bottom connected to the ends of said 105 walls opposite their hinges and disposed parallel with respect to the bottom of the body and spaced therefrom in a non-collapsed position whereby cushions are provided for the bottoms of the cells.

6. A carton comprising front, rear and bottom walls, a plurality of transverse cell walls, a longitudinal partition, and means connected to the cell walls for moving the latter to open and collapse the carton; said means coacting with the partition to lock the structure in open position.

7. A collapsible carton comprising front and rear walls, top and bottom walls connecting the same, a plurality of transverse cell walls formed from the top wall and movable to positions lateral thereto, a longitudinal partition intersecting said cell walls in non-collapsed position, and a flat 125 strip connected to the cell walls above the bottom wall for moving said cell walls into divers positions.

8. In a carton having a collapsible hollow body, a plurality of hinged cell walls co-op- 130

erating therewith, a longitudinal partition intersecting said cell walls, and a false bottom connected to the ends of said cell walls opposite their hinges; said false bottom being slotted longitudinally and disposed upon opposite sides of said partition.

9. A collapsible carton comprising front, rear and bottom walls, a plurality of transverse cell walls produced by slotting a

blank from which they hinge at their top 10 edges, and a separate flat strip connected to the lower ends of said cell walls and controlling the relative positions thereof.

Signed at Chicago, county of Cook and State of Illinois, this first day of March, 15 1923.

LOUIS SCHWARTZBERG.
